UNITED STATES PATENT OFFICE

WALTER T. WOODS, OF LONG BEACH, CALIFORNIA, ASSIGNOR, BY MESNE ASSIGNMENTS, TO BYRON JACKSON CO., OF SAN FRANCISCO, CALIFORNIA, A CORPORATION OF DELAWARE

ROCK DRILL

Application filed November 9, 1927. Serial No. 232,046.

This invention relates to rock drills of the type that are employed in drilling through hard rock formations by the hydraulic rotary method of drilling wells, such as oil 5 wells.

The present invention relates to a form of rock drill which is intended to operate in deepening a hole by presenting a roughened surface to the bottom of the hole which 10 rolls upon the bottom of the hole grinding and disintegrating the material therefrom. Drills of this class generally employ a plurality of cone cutting elements and said cone cutting elements are generally carried 15 by separate carriers.

An object of the present invention is to provide an improved form of drill of this class in which the means for attaching the cone carriers or supports is of an improved 20 form exceptionally durable in operation.

Another object of the present invention is to provide a means for attaching the cone carriers to the body of the drill, which attaching means is readily operated both to 25 attach the carriers to the drill and remove the same from the drill as required.

Another object of the present invention is to provide a rock drill of this type with an improved form of reamer and means for 30 attaching the reamer to the body of the drill.

Various further objects and advantages of the present invention will be understood from the description of a preferred form or 35 example of a rock drill embodying the invention. For this purpose, there is herein-after described with reference to the accompanying drawings the preferred form of rock drill.

Referring to the drawings:—

Figure 1 is an elevation mainly in vertical section of the rock drill;

Figure 2 is a transverse section on the line 2—2 of Figure 1;

Figure 3 is a transverse section on the line 3—3 of Figure 1; and

Figure 4 is a transverse section on the line 4—4 of Figure 1.

Referring to the drawings,—1 indicates 50 the body of the drill which is provided at

its upper end with a tapered and threaded pin 2 which provides a means by which the drill may be attached to a stand of drill pipe and rotated in a well hole. The lower end of the drill body 1 is shown as terminating in a threaded tapered socket 3 which provides a means for attaching to the body the cutting parts and carriers. The body 1 is also indicated as provided with a central passage 4, by means of which flushing fluid 55 may be passed through the drill to the cutters.

5 indicates the cutters of the drill, the drill being shown as preferably provided with three cutters and the cutters are indicated as of the conventional cone shape and provided with teeth 6 or other roughenings, by means of which the cutters may disintegrate the material at the bottom of the well hole when the drill is rotated so as to 60 roll the cutters thereover. The cutters 5 are indicated as mounted upon axes which are substantially at a 45° angle to the horizontal and the axes of the three cutters are indicated as converging at the axis of the 65 drill body 1. The cutting cones 5 are indicated as mounted by bushings 7 upon pins 8. The pins 8 are indicated as having one end set into a cutter carrier 9 and having the other end extending from the cutter 70 carrier and threaded as indicated at 10. The threaded ends of the pins 8 are preferably 75 screw threaded to the bushing 7 and between the bushing 7 and the cutter carriers there are provided washers or wear plates 11. 80 There is also provided a means for retaining the cutters upon the bushings, and said means is indicated as preferably comprising a metal ring 12 set in grooves in the cutters 85 and bushings 7.

The pins 8 may be integral with the cutter carriers 9 although in the preferred form of the invention the pins 8 are first made separate from the cutter carriers 9 and provided with tapered ends 13. The cutter 93 carriers 9 are provided with tapered openings 14 to receive the pins 8 and the pins 8 are secured to the cutter carriers 9 by welding the end of the pins to the carriers as indicated at 15.

The upper ends of the cutter carriers 9 terminate in pin portions 16 which together form an upwardly tapering threaded pin adapted to be screw threaded into the socket 3 of the body 1. The socket 3 thus provides a means for clamping the cutter carriers rigidly together. There is also preferably provided a means for clamping and holding the cutter carriers 9 together in addition to the socket 3, and for this purpose the cutter carriers 9 are indicated as together forming a hollow bore 17 which is provided near its lower end with an annular rib 18 both edges of which are cut inwardly as indicated at 19 and 20. A clamping ring 22 with a tapered socket 21 is indicated as positioned in engagement with the lower side 19 of the annular rib 18, and a second clamping rib 23 is indicated as having a tapered socket 20 engaging the side 20 of the annular rib 18 at the top of the rib. A clamping pin 24 is indicated as passing through a bore 17 formed by the cutter carrier and threaded into the lower clamping ring 22. Said 25 clamping pin is further indicated as provided with an annular rib 25 engaging the upper clamping ring 23 whereby the clamping pin 24 provides a means for forcing the clamping rings 22 and 23 against the rib 18 30 binding the three cutter carriers together. The clamping pin 24 is indicated as provided with a hollow bore or passage 26 which serves as a means for carrying the flushing fluid down to the cutters 5. The cutter carriers together form what may be termed a housing for the cutters 5, since the combined carriers 9 form a socket which houses the major portion of the cutters. The cutter carriers 9 might be described as formed by 35 vertically dividing such housing.

The drill is also preferably provided with one or more reaming rollers 27. Said reaming rollers 27 are preferably disposed to revolve about vertical axes and for this purpose are indicated as mounted upon shafts 28, the ends of which shafts are set in bearings 30. Washers or wear members 31 are indicated as disposed between the reaming rollers 27 and the bearings 30. The body of 40 the drill 1 is provided with recesses 32 for enclosing the major part of the reaming cutters 27 leaving only a portion of their cutting edge extending beyond the drill body. The drill body 1 is further provided with 45 recesses 33 for receiving the bearings 30 and said bearings 30 are indicated as being held to the drill body 1 by suitable means such as the screws or pins 34.

The rock drill herein described is of simple 50 and sturdy construction, and in practice it is found that the cutting elements are firmly secured to the drill body 1 so that there is no danger of any of the parts of the drill being lost in the well hole.

55 While the particular form of rock drill

herein described is well adapted to carry out the objects of the present invention, it is to be understood that many modifications and changes may be made without departing from the invention, and the invention includes all such modifications and changes as come within the scope of the following appended claims.

I claim:

1. In means of the class described, a 75 plurality of cutter carriers, cutters revolvably secured to said carriers, the carriers together forming a hollow bore, and clamping means in said bore clamping the carriers together.

2. A rock drill including a plurality of cutter carriers, cutters revolvably mounted by said carriers, said carriers forming an internal annular rib, and clamping means engaging said rib and operating to hold the 85 carriers together.

3. A rock drill of the class described, comprising a cutter housing vertically divided to form a plurality of cutter carriers, cutters revolvably mounted by said carriers, said 90 carriers being provided on their inner sides with adjacent rib portions, an axial clamping means engaging said rib portions for holding the cutter carriers together to form said cutter housing, said cutter housing providing a tapered threaded pin, and a drill body having a socket threaded to said pin.

4. A rock drill of the class described, comprising a body having a socket, a cutter housing having a hollow tapered pin threaded to said socket, said cutter housing being vertically divided into cutter carriers, cutters revolvably mounted by said cutter carriers, said carriers being provided with inner 100 rib portions, and axial clamping means engaging said rib portions for holding the cutter carriers together.

5. A rock drill of the class described, comprising a hollow cutter housing having an inwardly beveled, internal annular rib, the 110 cutter housing being vertically divided into a plurality of cutter carriers, cutters revolvably mounted by said carriers, beveled clamping rings engaging said annular rib, and a clamping member for pressing said 115 clamping rings against said rib.

6. A rock drill of the class described, comprising a plurality of cutter carriers, cutters revolvably mounted by said cutter carriers, said carriers being provided with adjacent rib portions, beveled clamping rings at adjacent sides of said rib portions, and a hollow clamping pin engaging said clamping rings.

7. A rock drill of the class described, comprising a cutter housing vertically divided into a plurality of cutter carriers, the housing forming a pin, cutting rollers revolvably mounted by said cutter carriers, a drill body having a socket threaded to said hous- 120

ing pin, and additional clamping means located within the axial center of said cutter carriers for holding the cutter carriers of said housing together when said housing is detached from said body.

5 Signed at Los Angeles, Calif., this 2d day of November, 1927.

WALTER T. WOODS.
